UNITED STATES PATENT OFFICE.

CHARLES W. HACK, OF TOPEKA, KANSAS, ASSIGNOR TO THE HOME REFRIGERATING COMPANY, OF TOPEKA, KANSAS, A CORPORATION OF KANSAS.

PISTON.

Application filed June 5, 1922. Serial No. 565,827.

To all whom it may concern:

Be it known that I, CHARLES W. HACK, a citizen of the United States, residing at Topeka, in the county of Shawnee and State of Kansas, have invented certain new and useful Improvements in Pistons; and I do declare the following to be a full, clear, and exact description of the invention, such as will enable others skilled in the art to which it appertains to make and use the same, reference being had to the accompanying drawings, and to the figures of reference marked thereon, which form a part of this specification.

15 This invention relates to a novel means for confining compressible fluid in the combustion chamber of a cylinder and the invention particularly contemplates an improvement in compressors.

20 It is the purpose of the invention to provide a cylinder and piston which will be so co-related that liability of leakage of the gas or compressible fluid past the piston will be reduced to a minimum if not entirely 25 eliminated.

Pistons are usually of metal and they are provided with packing rings which more or less serve the purpose intended. The lubrication of the piston with respect to the cylinder is always a problem. The metallic piston rings, too, have a tendency to score the cylinders and they frequently have to be replaced.

I have found that highly satisfactory results can be obtained by providing a piston having as a component part thereof lubricant absorbing fiber and I prefer to construct the piston of a non-metallic substance. The fiber can be, though not necessarily for all purposes, arranged in the form of sheets so that the edges of the sheets will have rubbing contact against the cylinder to polish it, the fabric and non-metallic substance eliminating the possibility of scoring the cylinder. The ends of the fibers are exposed at the surface of the piston so that they constitute lubricant-absorbing means, the fiber being adapted to be supplied with a lubricant in grooves in the piston; that is, the lubricant can be spread over the surface of the cylinder to be taken up by the capillary attraction of the fiber and reapplied to the cylinder surface as the piston reciprocates over it.

The piston is preferably formed of a material having substantially the same coefficient of expansion as the cylinder and I find that materials admirably adapted for the purpose are substances known commercially as "micarta" and "bakelite", with which the fiber is combined, although the fiber may be embedded in metal. The substances known as "micarta" and "bakelite", as is well known, are formed under high pressures, and where they are used, the fabric may be cotton, hemp, wood fiber or any suitable material. Where the fiber is to be combined with the metal, asbestos is recommended. The piston thus formed, if machined to a true fit, efficiently seals the cylinder; has a tendency to polish the surface due, it is believed, to the fiber present as well as the characteristics of the embedding material; and efficiently lubricates the same.

Actually I prefer to provide a metallic cylinder with a novel form of piston but if desired, the cylinder itself may be formed of a material having fiber as a component part thereof.

In actual practice, however, I have used the metallic cylinder with a novel form of piston and have found very satisfactory results throughout extended operating performance.

In order to fully appreciate the invention, reference should be had to the following description in connection with the accompanying drawings, in which

Fig. 1 is a fragmentary, longitudinal, sectional view through an air compressor to which my invention is applied.

Fig. 2 is an enlarged longitudinal sectional view through the piston.

Fig. 3 is a sectional view through one form of material of which the piston is made.

Fig. 2 is an exaggerated sectional view showing the alternate layers of the material and fiber; the rings 1 designate the material which alternates with the fiber or fabric layers 2. The material 1 is preferably a non-metallic substance, such as "bakelite" or "micarata" and the fiber is preferably arranged in sheets alternating with the rings 1. The ends of the fibers are exposed to the outer peripheral surface of the rings 1 so that they will come into contact with the cylinder 3 as the piston reciprocates therein.

The fiber sheets may be arranged as shown

in Fig. 2 or they may be arranged as shown in Fig. 3. The fiber may also be embedded in any appropriate manner in the material 1.

The piston may be provided with circumferential grooves 4, intermediate its ends but preferably near the compression end of the piston. The grooves are adapted to contain lubricant, such as oil, and during the reciprocation of the piston in the cylinder, the oil will be spread against the surface of the cylinder; part of it will initially be absorbed by capillary attraction set up by the fiber so that the fiber will become impregnated with the lubricant, thereby holding a reserve supply of lubricant to be redistributed over the cylinder, making the piston entirely self-lubricating.

The oil grooves will efficiently seal the cylinder, being assisted by the fibers and by the fact that the piston will be non-scoring since its consistency is such that it will not cut the inner surface of the cylinder. This I have demonstrated in actual practice.

As above stated, the cylinder may, under certain conditions, be formed of a material having fiber embedded therein but ordinarily

I prefer to construct the engine with a cylinder of metal and have the piston contain the fiber. I have recommended "micarta" and "bakelite" as being the best materials because they particularly lend themselves to a piston construction. I do not wish to be limited to these particular materials, however, because the fiber might be combined with or embedded with other material and satisfactorily perform the functions enumerated above.

What I claim and desire to secure by Letters-Patent is:

1. A non-metallic piston having fiber as a component part thereof, the ends of the fiber being exposed to the surface of the piston, and circumferential, lubricant-containing grooves in the periphery of the piston to supply lubricant to the fiber. 40

2. A non-metallic piston having fiber as a component part thereof, the ends of the fiber being exposed to the surface of the piston, and lubricant-containing recesses in the piston to supply lubricant to the fiber. 45

In testimony whereof I affix my signature. 50
CHARLES W. HACK.
